UNITED STATES PATENT OFFICE

JOSEPH L. SWEENEY, OF JACKSON HEIGHTS, NEW YORK, ASSIGNOR TO REMINGTON TYPEWRITER COMPANY, OF ILION, NEW YORK, A CORPORATION OF NEW YORK

TYPEWRITING MACHINE

Application filed July 2, 1927. Serial No. 203,129.

My invention relates to carrying cases for portable typewriting and like machines and to the combination of such a carrying case with the machine contained therein.

5 In carrying cases of the character specified, it is desirable to maintain the cubical dimensions thereof as small as possible consistent with the machine carried therein.

10 One of the main objects of the present invention, generally stated, is to provide a comparatively simple and inexpensive carrying case of the character specified provided with a chamber or compartment for containing stationery and other supplies without 15 unduly enlarging the carrying case.

20 A further object of the invention is to provide such a carrying case with simple and efficient means that will automatically coact with the typewriting machine, and certain 25 movable parts thereof, when the cover is closed and retain such parts against shifting movement.

25 To the above and other ends which will hereinafter appear my invention consists in 30 the features of construction, arrangements of parts and combinations of devices set forth in the following specification and particularly pointed out in the appended claims.

30 In the accompanying drawings wherein like reference characters designate corresponding parts in the different views:—

35 Fig. 1 is a vertical fore and aft sectional view of the carrying case with the machine shown in dotted lines enclosed therein; the section being taken on the line 1—1 of Fig. 2 and looking in the direction of the arrows at said line.

40 Fig. 2 is a transverse, vertical sectional view of the carrying case; the section being taken on the line 2—2 of Fig. 1 and looking in the direction of the arrows at said line.

45 Fig. 3 is a bottom plan view of the cover of the carrying case shown detached and with the false bottom removed.

50 Fig. 4 is a bottom plan view of the removable false bottom shown detached.

55 Fig. 5 is a detail face view of the spring retaining catch and some of the associated parts.

60 Fig. 6 is an enlarged, detail sectional view

of the same taken on the line 6—6 of Fig. 5 and looking in the direction of the arrows at said line.

The carrying case of the present invention is shown in the present instance combined 55 with a Remington portable machine, only so much of said machine being shown herein as is necessary to arrive at an understanding of my invention in its cooperation therewith. It should be understood, however, that the 60 carrying case is not restricted to use in combination with such machine but may be used in conjunction with other typewriting or like machines wherever found available.

The typewriting machine includes a frame 65 1 on which is mounted a carriage 2 supported to travel in a line feed direction under control of the usual escapement mechanism, and carrying a cylindrical platen 3. The carriage is supported on a case shift frame, shown in 70 part at 4, mounted on four supporting arms or links, one of which is shown at 5, to receive a case shifting movement fore-and-aft of the machine and carry the carriage 2 and platen 3 with it. The carriage is provided with end 75 plates 6 which have rearwardly projecting extensions 7, as shown in Fig. 1. The normal position of the carriage is that shown in Fig. 1, and in the operation of the machine the carriage is shifted from time-to-time rear- 80 wardly from such position to bring the platen in position to receive the impact of the upper case types on the type bars. Means, such as the resilient contacts 8, are provided which are automatically brought into contact with 85 the rearward extensions 7 on the carriage when the cover is closed and thereby prevent a case shifting movement of the carriage, the platen, the case shift frame and the various parts carried thereby, as will hereinafter 90 more clearly appear.

The carrying case for the machine comprises a flat member 9 which constitutes the bottom of the two-part carrying case and also the baseboard of the typewriting machine 95 which is permanently, though detachably, secured thereto, as will presently appear. The other member of the carrying case is a cover section having a top wall 10, rear wall 11, a front wall 12 and side walls 13. All of these 100

walls are permanently united to form a box-like cover that entirely encloses the machine on all sides except the bottom which is enclosed by the baseboard of the typewriting machine that likewise constitutes part of the carrying case, as hereinbefore pointed out.

Referring more particularly to Fig. 1 it will be seen that the frame of the machine is fixed to the baseboard by detachably united connections, such for example as are disclosed in the patent to Holden No. 1,587,484 dated June 1, 1926. Each of these connections comprises a screw or member 14 having a threaded connection with a metallic member 15 that carries rubber feet 16 below the baseboard. The machine frame is firmly secured to the baseboard by each cooperative pair of connecting members acting on the machine frame and baseboard through an interposed rubber member 17. There are several objects in view in firmly uniting the machine to the baseboard in the manner indicated. In the first place, the machine as a whole is firmly held within the carrying case while the machine is enclosed and being carried about in the case. In the second place, the combined case bottom and baseboard constitute a permanent bottom for the machine, and a protection for comparatively delicate working parts thereof, which in the absence of said baseboard might be exposed to injury while the machine is in use. This baseboard thus attached to the machine enables it to be readily used as a lap-board to support the machine on the knees of the operator without liability of injury to the working parts of the machine, and without in any manner interfering with the operation of the machine supported in this manner, which in practice has proved to be a convenient manner of using the machine.

It will be seen that when the cover is in place it receives therein the baseboard, the bottom edges of the cover being substantially flush with the bottom of the baseboard. In this manner the cover efficiently coacts with the baseboard to receive the weight thereof with the attached machine, and yet provides a carrying case which as a whole presents a neat appearance. The cover is detachably connected to the baseboard preferably at the front and rear edges of the latter. The means for detachably connecting the cover to the baseboard in the present instance are the same as those heretofore used in connection with the Remington portable carrying case. Such means comprises two forwardly projecting metallic fingers 18 secured to the cover near the lower edge of the rear wall 11 thereof. Each plate 19 from which a finger 18 is formed is apertured at 20 (Fig. 2) beneath the finger, the wall 11 of the cover having a cut-out portion 21 opposite each opening 20. Two rearwardly projecting fingers 22 are attached to the baseboard and are adapted to be received

within the registering openings 20 and 21, as shown in Fig. 1. These means enable the cover to receive a swinging pivotal motion around the rear edge of the baseboard to the closing position, shown in Fig. 1, and to be readily attached to or detached from the baseboard when desired.

The front wall 12 of the cover may be readily connected to or detached from the baseboard by suitable means such for example as the lock disclosed in the patent to Holden 1,507,355 dated September 2, 1924 and which comprises a pivotal hasp 23 having a locking projection 24 adapted to pass through a keeper on the baseboard, said keeper extending into the opening 25 of the lock when the cover is closed.

The front wall 12 of the cover is provided with a handle 26 by which the case and enclosed machine may be conveniently carried with the rear end of the machine lowermost.

In accordance with the present invention the cover is provided with one or more compartments or chambers, three such compartments 27, 28 and 29 being shown in the present instance. These compartments are for receiving stationery or suitable supplies such for example as paper, envelopes, erasers and pencils, represented in Fig. 3 by the reference numerals 30, 31, 32 and 33 respectively. These compartments are preferably divided by partition walls 34 and 35 that extend down from the top wall 10 of the cover fore-and-aft thereof throughout, or substantially throughout, the length of the cover. A plate-like false bottom or dividing member or wall 36 rests on the bottom edges of the partition walls 34 and 35 and is detachably secured in place thereon and in the cover, as will be presently described, to close the compartments or chambers 27, 28 and 29 and confine the supplies therein when the cover is closed and secured to the baseboard. When, however, the cover is removed and inverted the false bottom may be removed, giving access to the supplies contained within the chambers 27, 28 and 29.

In the present instance the means for detachably securing the member or false bottom 36 in place comprises a pair of angular sheet metal brackets or cleats 37 each having its foot piece secured to the rear wall 11 of the cover, the bracket arm or flange of each bracket extending forward into the cover. These brackets coact with the under side of the rear edge of the dividing member 36, as shown in Fig. 1, to support it in place and confine it between the lower edges of the partition walls 34 and 35 and said brackets. The front end of the member 36 has a tack 38 driven therein, said tack having a head 39 which projects forward from the edge of the dividing member and is provided with a flattened engaging edge 40 at the lower side thereof, as shown in Figs. 5 and 6. A plate-like spring catch 41 is con-

nected at its lower end, as at 42, to the inner side of the front wall 12 of the cover. The upper edge 43 of the catch is adapted to engage beneath the engaging edge 40 of the projection 39 and thus hold the forward end of the dividing member 36 up in contact with the lower edges of the partition 34 and 35. The spring catch 41 is provided with two upstanding fingers 44 at the upper edge thereof. These fingers are adapted to coact with the front end of the dividing member 36 and limit the backward movement of the free end of the catch and prevent it from passing at its upper end beneath the dividing member 36. The power of the spring catch is exerted to move the free end thereof rearward to locking position. When the cover is removed and inverted, the spring catch is forced forward with one hand to 10 release it from the projection 39, while the operator with the other hand may grasp the leather finger piece 45 and lift the dividing member 36 at the forward end, at the same time drawing it slightly forward to release the 20 rear end thereof from the brackets 37. The dividing member may then be removed, giving access to the supplies contained in the chambers 27, 28 and 29. Before the cover is replaced to enclose the machine, the rear end 30 of the dividing member 36 is placed beneath the brackets 37 and the forward end dropped. As the forward end of the dividing member drops into closed position the projection 39 thereon will coact with the spring catch cam- 35 ming it forward until said projection passes the free end of the catch when the latter will spring forward into engagement with said projection and thus automatically lock and hold the dividing member in place in the 40 cover. The cover may then be replaced to enclose the machine and be locked to the base- board.

If desired headed tacks 46 may be driven into the partitions 34 and 35 and rubber bands 47 may be looped over said tacks and stretched across over the stationery contained in the chamber 28 to hold it in place therein.

I prefer to secure depending rubber buffers or contacts 48 and 49 on the under side of the dividing member 36, the former being adapted to bear down on the frame of the machine, and the latter to bear down on the platen when the cover is closed, as shown in Fig. 1. I also prefer to employ a depending block or contact 50 near each side of the dividing member 36, and which are secured alone to said dividing member. When the cover is closed each of these blocks inter- 60 poses itself between a side of the frame of the typewriting machine and the associated side wall 13 of the cover, as indicated in Fig. 2. As previously pointed out the contacts 8 on the rear wall 11 of the cover are auto- 65 matically brought against the projections 7

on the carriage when the cover is closed. It will be seen therefore that at this time the carriage, the platen carried thereby and the case shift frame and other parts carried thereby are firmly held against case shifting movement from normal position on the frame of the machine by the contacts 8 and 49. Moreover, the frame of the machine is not only held securely to the baseboard by the connections 14 and 15 but also is held firmly in 70 the cover by the contacts 48 and 50 bearing against the machine frame. The reaction of the rubber contacts 48 and 49 bearing on the frame of the machine and the platen respectively tends to firmly hold the member 80 36 against the partition walls 34 and 35 on which it is seated, thus preventing any rattling or lost motion of the member 36 in the case.

I also prefer to employ a spring clip 51 secured at its base, at 52, to the under side of the dividing member 36, and which is adapted to hold a type cleaning brush or other implement 53. It will be understood that access may be had to this brush without removing the dividing member 36 from the cover. 85 90

If desired strengthening blocks 54 may be secured in the ends of the compartments 27 and 29, such blocks being of a depth substantially equal to the depth of such compartment, or the distance between the under face of the top wall 10 of the cover and the lower edge of the associated partition wall 34 or 35. Upright triangular strengthening 100 strips 55 also may be secured in the corners of the cover, the corners of the dividing member 36 being cut away at 56 to accommodate said corner strips 55.

It will be seen that the detachable member 36 divides the cover in at least two compartments, one a compartment for supplies located between said member 36 and the top wall 10 of the cover, and the other a machine-containing-compartment between the 110 members 36 and the flat baseboard 9 of the machine, and that the supplies contained in said first mentioned compartment are maintained separated from the machine-containing-compartment by the dividing mem- 115 ber 36 when the cover is closed and the machine is being carried within the case.

From the foregoing description it will be understood that I have provided a simple, compact, comparatively inexpensive carrying case, which is neat in appearance and the cubical dimensions of which are about as small as are consistent with the purposes of said case and the functions it performs in 120 combination with the typewriting machine contained therein.

Various changes may be made in the construction, and parts thereof may be employed without others, without departing from the 130

invention as it is defined in the accompanying claims.

What I claim as new and desire to secure by Letters Patent, is:—

- 5 1. A carrying case for a portable typewriting machine comprising a typewriter baseboard on which the machine is secured, an enclosing cover detachably connected to said baseboard, a detachable and removable dividing wall in the cover between the top thereof and the baseboard which dividing wall when in place is carried by the cover and provides a chamber in the cover between the top wall thereof and said dividing wall in which stationery and supplies may be received and kept apart from the machine contained within the space between said dividing wall and the baseboard, access being gained to the stationery chamber by a removal of said dividing wall when the cover is detached, partition walls in said stationery containing chamber on which said removable dividing wall is adapted to rest, a cleat on the cover that coacts with one end of said removable dividing wall when the latter is in place in the cover to prevent said dividing wall from being displaced off said partition walls, and a releasable catch on the cover coacting with the opposite end of said dividing wall to hold it in place in the cover.
- 10 2. A carrying case for a portable typewriting machine comprising a baseboard on which the machine is secured, an enclosing cover detachably connected to said baseboard, a removable dividing wall in the cover between the top thereof and the baseboard which dividing wall when in place is carried by the cover and provides a chamber in the cover between the top wall thereof and said dividing wall in which stationery and supplies may be received and kept apart from the machine contained within the space between said dividing wall and the baseboard, access being gained to the stationery chamber by a removal of said dividing wall when the cover is detached, partition walls in said stationery-containing chamber on which said removable dividing wall is adapted to rest, a cleat on the cover that coacts with one end of said removable dividing wall when the latter is in place in the cover to prevent said dividing wall from being displaced off said partition walls, a releasable catch on the cover coacting with the opposite end of said dividing wall to hold it in place on the cover, and one or more contacts on said dividing wall which bear against the machine when the dividing wall is in place in the cover and the cover is closed.
- 15 3. Signed at the borough of Manhattan, city of New York, in the county of New York and State of New York this 1st day of July A. D. 1927.

JOSEPH L. SWEENEY.
